(57) **CLAIM**

I claim the ornamental design for the modular free float tube for a firearm, as shown and described.

DESCRIPTION

FIG. 1 is a perspective view of a modular free float tube for a firearm;

FIG. 2 is a first perspective view of a modular free float tube for a firearm;

FIG. 3 is right side view of a modular free float tube for a firearm;

FIG. 4 is a left side view of a modular free float tube for a firearm;

FIG. 5 is a top view of a modular free float tube for a firearm;
FIG. 6 is a bottom view of a modular free float tube for a firearm;

FIG. 7 is a front view of a modular free float tube for a firearm;
and,

FIG. 8 is a rear view of a modular free float tube for a firearm.
The break lines in the drawing views 1 through 6 indicate that a specific length of the claimed design does not form a part of the claimed design.
